UNITED STATES PATENT OFFICE

121,884

DESIGN FOR AN ATOMIZER

Arthur W. Pitts, Tacoma, Wash.

Application June 17, 1940, Serial No. 93,040

Term of patent 14 years

To all whom it may concern:

Be it known that I, Arthur W. Pitts, a citizen of the United States of America, residing at Tacoma, in the county of Pierce and State of Washington, have invented a new, original, and ornamental Design for Atomizers, of which the following is a specification, reference being had to the accompanying drawing, forming part thereof.

Figure 1 is a side elevational view of an atomizer embodying my new design;

Figure 2 is a front elevational view thereof with the air bulb and tubing omitted for convenience of illustration; and

Figure 3 is a cross-sectional view taken at any point intermediate the base of the angled discharge nozzle and the air inlet hole which is shown in Figure 1.

The dominant features of my design reside in the portions shown in full lines.

I claim:

The ornamental design for an atomizer, substantially as shown and described.

ARTHUR W. PITTS.
